UNITED STATES PATENT OFFICE

EARL D. ALLEN, OF SPOKANE, WASHINGTON

DESIGN FOR A COMBINED ELECTRIC LAMP AND PICTURE FRAME

Application filed May 3, 1933. Serial No. 47,981. Term of patent 3½ years.

To all whom it may concern:

Be it known that I, EARL D. ALLEN, a citizen of the United States, residing at Spokane, in Spokane County and State of Washington, have invented a new, original, and ornamental Design for Combined Electric Lamp and Picture Frame, of which the following is a specification, reference being had to the accompanying drawing forming a part thereof, in which

Fig. 1 is a front perspective view of a combined electric lamp and picture frame showing my new design; and Fig. 2 is a rear perspective view of the same.

I claim:

The ornamental design for a combined electric lamp and picture frame, substantially, as shown.

EARL D. ALLEN.
